UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS SONS & MAXIM, LIMITED, OF LONDON, ENGLAND.

AUTOMATIC GUN.

No. 909,849.

Specification of Letters Patent.

Patented Jan. 12, 1908.

Original application filed October 23, 1907, Serial No. 398,718. Divided and this application filed July 6, 1908. Serial No. 442,109.

To all whom it may concern:

Be it known that I, ARTHUR TREVOR DAWSON, lieutenant Royal Navy, director and superintendent of ordnance works, and GEORGE THOMAS BUCKHAM, engineer, both subjects of the King of Great Britain, residing at 32 Victoria street, Westminster, in the county of London, England, have invented certain new and useful Improvements in or Relating to Automatic Guns, of which the following is a specification.

This invention relates to automatic guns, particularly those of the Maxim rifle caliber pattern, the chief object being to provide a gun of this character arranged so as to enable the feed block and the breech mechanism to be readily accessible independent of each other.

According to this invention the cover plate of the breech casing and that of the feed block are both pivoted to the same axle in such a manner that said feed block can be reached without opening the cover of the breech casing, or the lock can be reached without opening the cover of the feed block.

We will describe our invention with reference to the accompanying drawing which gun having our improvement applied thereto.

B is the breech chamber, and D the feed block. B' and D' are the cover plates of the breech chamber and feed block respectively, said cover plates being mounted on the same axle or pivot pin d. The feed block can thus be reached without opening the said cover

B' of the breech casing, a spring catch b' 35 being provided on the cover D' for retaining it closed.

In the accompanying drawing we have illustrated our improvement applied to a gun having breech mechanism of the kind forming the subject matter of our United States Patent application Serial No. 398718, filed October 23rd, 1907, but we wish it to be understood that the improvement forming the subject matter of the present application 45 is also applicable to Maxim automatic rifle both pivoted to the same axle.

What we claim and desire to secure by Letters Patent of the United States is:—

1. In an automatic gun of the Maxim type, 50 the combination with the breech casing and the feed block, of cover plates for the same, both pivoted to the same axle.

2. In an automatic gun of the Maxim type, 55 the combination with the breech casing and the feed block, of an axle situated between them, and cover plates for the aforesaid breech casing and feed block both pivoted to the said axle.

In testimony whereof we have hereunto 60 set our hands in presence of two subscribing witnesses this eleventh day of June 1908.

ARTHUR TREVOR DAWSON,
GEORGE THOMAS BUCKHAM.
